UNITED STATES PATENT OFFICE.

RANSOM ALBERT GROUT, OF SAN BRUNO, CALIFORNIA.

TELEGRAPH RECEIVING INSTRUMENT.

Application filed January 5, 1926. Serial No. 79,372.

This invention relates to a telegraph receiving instrument, which has been perfected with the object of amplifying the sound thereof by means of a simple and inexpensive device, which is reliable and efficient and easily actuated. The present construction embodies some of the features shown in U. S. Patent 1,066,410, issued to me July 1, 1913, but some of the more cumbersome parts of the latter have been eliminated, and other improvements have been effected with the result that the present instrument is more compact and serviceable, and is capable of finer and readier adjustment. The specific construction of the invention and the advantages thereof will be more fully explained in the following detailed description, which is to be read in connection with the accompanying drawing, illustrating the same in its preferred form.

In the drawing:

Figure 1 is a side elevation of the invention with parts thereof broken away and shown in section.

Figure 2 is a vertical longitudinal section through the front part of the instrument.

Figure 3 is a transverse section taken on the line 3—3 of Figure 2.

Figure 4 is a transverse section taken on the line 4—4 of Figure 2.

Figure 5 is a section taken on substantially the same plane as Figure 3, but looking in the opposite direction as indicated by the arrows 5—5 in Figure 2.

The instrument, constituting the subject matter of the invention, comprises a magnet 10, of the usual construction, mounted for longitudinal adjustment in a sleeve 11, which is clamped in a bracket 12 secured to a suitable base 13. Binding posts 14 are secured to the rear end of the base 13, and are operatively connected by wires 15 to the magnet 10.

A cap 16 is secured to the rear end of the sleeve 11, and the core 17 of the magnet has a threaded stem 18 secured to its rear end and extending rearwardly through a central orifice in the cap 16, and through a bore in the upper end of a post 19, which is secured to the base 13. A coiled spring 20 surrounds the stem and bears against the rear end of the core 17, and the longitudinal adjustment of the magnet is determined by means of an adjusting nut 21 and a lock nut 22 mounted on the threaded end of the stem 18. The front end of the sleeve

11 is threaded to receive an annular head 23 to which a diaphragm holder 24 is secured by means of clamping plates 25. The periphery of the diaphragm holder has an inverted flange 26, beneath which are secured two rings or washers 27 with the diaphragm 28 between them. The front cover plate 29 is also secured beneath the flange 26, and has a forwardly extending collar 30 secured centrally thereof, and constituting a bearing to receive the rearwardly extending neck 31 of the horn 32.

The central portion of the diaphragm 28 is cut away to receive a collar 33, having at its rear end an annular head 34 constituting an anvil, the collar being externally threaded to receive a clamping nut 35. Suitable clamping rings or washers 36 are mounted on the collar 33, and cooperate with the nut 35 and head 34 to clamp the anvil rigidly to the center of the diaphragm, so that the sound of any blow received by the anvil will be transmitted directly to the diaphragm and will be emitted from the horn 32.

The inner portions of the plates 25 are turned rearwardly, as shown at 37, to provide a space for the sounding element which delivers the strokes to the anvil 33. This sounding element comprises a rectangular head 38 secured to the end of a non-circular stem 39, which is guided centrally of the diaphragm 28 and perpendicular thereto by a guideway 40 supported by arms 41, which are secured to the inside of the collar 30. The stem 39 extends beyond the non-circular portion in the form of a threaded spindle 42, on which is mounted an adjustable nut 43 and lock nut 44, which adjustably limit the stroke of the sounding element 38, and also serve to counterbalance the same.

The sounding element 38 acts as an armature for the core 17 of the magnet, and is actuated in one direction by the magnet, and in the other direction by a coiled spring 45. This spring is connected at one end to the spindle 42, and at the other end to a pin 46, which is swivelled in a screw 47 mounted in the outer end of a bracket 48 secured to and extending forwardly from the collar 30. The screw 47 may be adjusted to vary the tension of the spring 45, and may be secured in adjusted position by a lock nut 49.

The major adjustment of the magnet 10 may be effected by a manipulation of the nuts 21 and 22, and a finer adjustment may

be effected by rotating the head 23 on the sleeve 11, thereby moving the diaphragm and anvil toward or from the magnet. The length of stroke of the sounding element is regulated by means of the nuts 43 and 44. The tension of the spring 45 is varied by means of the screw 47 and lock nut 49. All of these adjustments may be made with one hand, while the other hand is free to work 10 the key.

A further and important advantage of the present construction is the manner in which the blow of the sounder is delivered, and the manner in which the sound is transmitted 15 and amplified by the diaphragm and horn. The anvil 34 is secured in direct and rigid contact with the diaphragm, and the sounding element 38 is balanced and guided, so that it has a free and easy rectilinear movement toward and from the anvil. By delivering the blow in exactly the center of the diaphragm and directly on the anvil, sound produced by the instrument is much louder, 20 operates with less current, and is capable 25 of much finer adjustment.

While I have shown the invention in connection with only one magnet, it is, of course, to be understood that two magnets may be used if desired without any material 30 change in the construction of the sounder and amplifier. It is apparent that various modifications may be made in the details of construction and the arrangement of the same without any material departure from 35 the salient features of the invention as claimed.

What is claimed is:

1. In a telegraph receiving instrument, the combination of a magnet, a diaphragm 40 mounted in front of the magnet, an anvil secured centrally to the diaphragm, and a sounding element acting as an armature and guided for rectilinear movement between the anvil and the core of the magnet.

45 2. In a telegraph receiving instrument, the combination of a magnet, a diaphragm mounted in front of the magnet, an anvil secured centrally to the diaphragm, a reciprocable sounding element acting as an armature, and means for supporting said element independently of the diaphragm and for guiding it rectilinearly between the anvil and the core of the magnet.

50 3. In a telegraph receiving instrument, the combination of a casing, a magnet mounted within the casing, a diaphragm in front of said magnet, a horn extending forwardly in front of the diaphragm, an anvil secured centrally of the diaphragm, a sounding element guided for rectilinear movement between the anvil and the core of the magnet, a bracket secured to the neck of the horn, a pin located centrally of the horn and secured to the bracket, and resilient means 55 connected with the pin and cooperating with

the magnet to reciprocate the sounding element.

4. In a telegraph receiving instrument, the combination of a magnet, a diaphragm mounted in front of the magnet and having an opening through its center, a collar secured to the edge of said opening and having a flange constituting an anvil on the side toward the magnet, and a sounding element guided for movement between the anvil and 75 the core of the magnet.

5. In a telegraph receiving instrument, the combination of a magnet, a diaphragm mounted in front of the magnet and having an opening through its center, a collar secured to the edge of said opening and having a flange constituting an anvil on the side toward the magnet, a guide member located centrally of the collar and perpendicular to the diaphragm, means supporting said guide member so that it is not in contact with either the diaphragm or the collar, and a sounding element supported for reciprocation by said guide member and having a head which moves between the anvil and 80 the core of the magnet.

6. In a telegraph receiving instrument, the combination of a magnet, a diaphragm mounted in front of the magnet and having an opening through its center, a collar secured to the edge of the opening and having a flange constituting an anvil on the side toward the magnet, a guide member located centrally of the collar and perpendicular to the plane of the diaphragm, a stem mounted 95 for reciprocation in said guide member, a head secured to one end of the stem and constituting an armature, and sounding element which is movable between the anvil and the core of the magnet, and a nut secured to the other end of the stem and counterbalancing the head, said nut being adjustable to adjust the length of stroke of the sounding element.

7. In a telegraph receiving instrument, the combination of a casing, a magnet mounted within the casing, a diaphragm in front of the magnet, an anvil secured centrally of the diaphragm, and a sounding element having a shank guided for rectilinear movement 110 centrally of the diaphragm and perpendicular thereto and having a head adapted to strike the anvil and the core of the magnet alternately.

8. In a telegraph receiving instrument, the combination of a casing, a magnet mounted within the casing, a diaphragm in front of said magnet and having a central opening therethrough, a collar secured to the diaphragm around said central opening and constituting an anvil, a reciprocable sounding element between the anvil and the core of the magnet, said sounding element having a shank extending through said anvil centrally of the diaphragm, and means for in- 115 120 125 130

dependently supporting said element out of contact with the diaphragm and anvil and for guiding it rectilinearly, so that the sounding element reciprocates between the anvil and the core of the magnet.

9. In a telegraph receiving instrument, the combination of a casing, a magnet mounted within the casing, a diaphragm holder connected with the front end of the casing, a diaphragm clamped in said holder, a horn supported by said holder and extending forwardly in front of the diaphragm, an anvil secured centrally of the diaphragm, a sounding element having a shank guided for movement centrally of the diaphragm and perpendicular thereto and having a head adapted to strike the anvil and the core of the magnet alternately, and means supported centrally of the horn and cooperating with the magnet to reciprocate said sounding element.

10. In a telegraph receiving instrument, the combination of a cylindrical casing, a magnet mounted within the casing, a diaphragm in front of said magnet, a holder for the diaphragm having a screw threaded connection with the casing, whereby to adjust the distance between the diaphragm and the magnet, said diaphragm having an open-

ing through its center, a collar secured to the edge of said opening and having a flange constituting an anvil on the side toward the magnet, a sounding element guided for movement between the anvil and the core of the magnet, and means cooperating with said magnet to actuate the sounding element.

11. In a telegraph receiving instrument, the combination of a cylindrical casing, a magnet mounted within the casing, a diaphragm in front of said magnet, a holder for the diaphragm having a screw threaded connection with the casing whereby to adjust the distance between the diaphragm and magnet, said diaphragm having an opening through its center, a collar secured to the edge of said opening and having a flange constituting an anvil, a guide member located centrally of the collar and perpendicular to the plane of the diaphragm, a sounding element supported for reciprocation by said guide member and having a head which moves between the anvil and core of the magnet, and means cooperating with the magnet for actuating said sounding element.

In testimony, that I claim the foregoing as my own, I have hereto affixed my signature.

RANSOM ALBERT GROUT.
